US00D809078S

(12) United States Design Patent (10) Patent No.: US D809,078 S
(45) Date of Patent:  Jan. 30, 2018

(54) GOLF CLUB HEAD COVER

(71) Applicant: KARSTEN MANUFACTURING CORPORATION, Phoenix, AZ (US)
(72) Inventors: Martin R Jertson, Cave Creek, AZ (US); Daniel K Lee, Chandler, AZ (US)

(73) Assignee: Karsten Manufacturing Corporation, Phoenix, AZ (US)

() Term: 15 Years

(21) Appl. No.: 29/578,687

(22) Filed: Sep. 23, 2016

(51) LOC (11) Cl. 21-02

(52) U.S. Cl. USPC D21/754

(58) Field of Classification Search

USPC D21/754

CPC A63B 60/00; A63B 60/62

See application file for complete search history.
